US0D1093642S

(12) **United States Design Patent** (10) **Patent No.:** **US D1,093,642 S**
(45) **Date of Patent:** **** Sep. 16, 2025**

(54) **SKIN AESTHETIC APPARATUS**

(71) Applicant: **CERAGEM CO., LTD.**,
Chungcheongnam-do (KR)

(72) Inventors: **Junghyun Jo**, Gyeonggi-do (KR);
Jongoh Lee, Gyeonggi-do (KR);
Daesung Kim, Seoul (KR)

(73) Assignee: **CERAGEM CO., LTD.**,
Chungcheongbuk-Do (KR)

(**) Term: **15 Years**

(21) Appl. No.: **29/949,234**

(22) Filed: **Jun. 26, 2024**

(30) **Foreign Application Priority Data**

Dec. 27, 2023 (KR) 30-2023-0053091
Jun. 12, 2024 (KR) 30-2024-0022972

(51) **LOC (15) Cl.** **28-03**

(52) **U.S. Cl.**

USPC **D24/214**

(58) **Field of Classification Search**

USPC D24/200, 214, 211
CPC A61N 1/327; A61N 1/328; A61N 1/18

(57) **CLAIM**

The ornamental design for a skin aesthetic apparatus, as shown and described.

DESCRIPTION

FIG. 1 is a perspective view of the skin aesthetic apparatus, showing our new design;

FIG. 2 is a front view of the skin aesthetic apparatus;

FIG. 3 is a rear view of the skin aesthetic apparatus;

FIG. 4 is a left side view of the skin aesthetic apparatus;

FIG. 5 is a right side view of the skin aesthetic apparatus;

FIG. 6 is a top view of the skin aesthetic apparatus; and,

FIG. 7 is a bottom view of the skin aesthetic apparatus.

1 Claim, 7 Drawing Sheets

FIG. 1

FIG. 2

FIG. 3

FIG. 4

FIG. 5

FIG. 6

FIG. 7
